UNITED STATES PATENT OFFICE

158,642

FIGURINE

Fred Braunberger, Fargo, N. Dak.

Application May 13, 1948, Serial No. 146,349

Term of patent 3½ years

(Cl. D29—23)

To all whom it may concern:

Be it known that I, Fred Braunberger, a citizen of the United States, residing at Fargo, North Dakota, have invented a new, original, and ornamental Design for Figurines, of which the following is a specification, reference being had to the accompanying drawing forming part thereof.

In the drawing:

Fig. 1 is a side elevational view in perspective of a figurine showing my new design, the opposite side being substantially the same as that shown;

Fig. 2 is a front end view thereof; and

Fig. 3 is a rear end view of the same.

The dotted line showing of the clock in Fig. 1 is illustrative only.

I claim:

The ornamental design for a figurine, as shown and described.

FRED BRAUNBERGER.
